(57) **CLAIM**

The ornamental design for a lighter with smoker's tools, as shown and described.

DESCRIPTION

FIG. 1 is a rear, top, left-side perspective view with tools folded out of a lighter with smoker's tools showing our new design;

FIG. 2 is a top plan view thereof with inwardly folded tools;

FIG. 3 is a bottom plan view thereof;

FIG. 4 is a top, front perspective view thereof;

FIG. 5 is a top right side perspective view thereof;

FIG. 6 is a right side elevational view of FIG. 1; and,

FIG. 7 is a rear view thereof with the tools folded in.
